UNITED STATES PATENT OFFICE.

GALEN COFFIN, OF BOSTON, MASSACHUSETTS.

SAW-CLAMP.

SPECIFICATION forming part of Letters Patent No. 319,455, dated June 9, 1885.

Application filed May 9, 1884. (No model.)

To all whom it may concern:

Be it known that I, GALEN COFFIN, of Boston, in the county of Middlesex and State of Massachusetts, have invented a new and useful Improvement in Saw-Clamps, of which the following, taken in connection with the accompanying drawings, is a specification.

My invention consists of an improvement in what is known as a clamp or a holding device for filing saws, and is especially adapted to circular saws; and it consists of two upright pieces or clamping-jaws, between which the saw is clamped, and a pin passing through the center hole of the saw, on which it revolves as it is filed, together with a third upright bar, from one edge of which project several wedge-shaped pieces, which serve, in connection with the central pin, to draw the two clamping-jaws together, thereby holding the saw firmly in position for filing.

To enable those skilled in the art to make and use my improved saw-clamps, I will proceed to describe the same with reference to the drawings, similar letters referring to similar parts.

Figure 1 represents a front view of my invention. Fig. 2 is a side view of the same in section as it would appear when fastened to a common bench. Fig. 3 represents a cross-section through the center of a circular saw when in position for filing. Fig. 4 represents a cross-section near the lower end.

In the drawings, Fig. 1, A.B are the two upright clamps between which the saw is held. C is an upright bar swinging from a fulcrum, as seen at f in Figs. 2 and 3, and having a series of wedge-shaped pieces, as c c c c c, projecting from one edge, and also a raised piece near the upper end, for convenience of driving the top end forward or back when clamping or releasing the saw. a is a long slot running up and down for any desired part of the length of the clamp or jaw A.

b b b b are holes in the clamp B, placed at suitable distances apart to accommodate the different sizes of saws. These holes are somewhat less in width than the diameter of the pin D, the front end of which is cut away correspondingly, to insure its projecting end being in the right position to enable one of the

wedge-pieces c c c c to pass through hole d in the pin D.

The clamping-jaws A B may be made of either wood or metal, but are herein represented as if made of cast-iron, and have several holes cut through each, as m m m m m, merely to lighten them. The clamp-piece A is also provided with screw-holes, as h h, to fasten the same to a bench. There are also two holes near the lower end, passing through both A and B, for two small bolts or screws, as i i, which serve to hold the two clamping-jaws firmly together.

The swinging bar C is provided with a round piece projecting from the back side of its lower end, which passes through the hole g in the clamp-piece A, while it also rests in the pocket-shaped cavity or bracket, as E, in the front jaw, B, thereby holding its lower end firmly in position, while the upper end is allowed to swing freely back and forth, but cannot be removed from its place without first removing the bolts or screws i i.

To use my improved saw-clamp, I take the clamp-piece B and insert the lower end of the swinging bar C in the pocket, as E. I then place both upon the piece A, so that the pin f fits into the hole g; then, holding the two jaws in their proper position, put in the two bolts or screws i i, screwing them firmly together with a screw-driver. The whole is then secured to a bench by means of common wood-screws. The pin D is then taken in one hand and placed in the slot a, and with the other hand place the saw between the clamps A B, while the pin D is then passed through the saw and one of the holes b b b b, according to size of the saw, and the corresponding wedge-piece, c c c c, is driven through the hole d in the pin D by a blow with the hand, where the saw is held in position and freely revolved upon the pin D until filed, when it is instantly released by another blow with hand or handle of the file.

The construction of the pin D can be varied by dispensing with the hole d, and turning the corresponding part to a smaller diameter, in which case the wedge-pieces would be double or forked, and the holes in the jaw B would be round; but as it is sometimes troublesome

removing the pin D without its catching the saw, I prefer the construction shown in the drawings.

In case the clamping jaws A B are made of wood, the wedge-carrying bar can be provided with a screw-hole to fasten it to the jaw B, instead of the devices shown in the drawings. It is obvious, also, that a single wedge can be substituted for the swinging bar C with its several wedge-shaped projections; but the form shown and described will be found much more convenient.

If desired, long wood-screws may be used instead of the bolts *i i*, in which case the nuts shown on the bolts would not be wanted, as the screws would pass through both A and B into the bench, securing the whole in position for use.

Having thus described my invention, what I claim as new, and desire to secure by Letters Patent, is—

1. The combination of the jaw A, provided with slot *a*, the jaw B, provided with holes *b b*, the pin D, and the wedge C, arranged to co-

operate with each other to force said jaws toward each other, substantially as described.

2. The combination of the jaw A, provided with the hole *g*, the jaw B, provided with the pocket E, the pin D, the swinging wedge-carrier C, provided with pin *f*, and the bolts or screws *i i*, all arranged and adapted to operate substantially as and for the purpose set forth.

3. In combination with the jaw A and the jaw B, provided with holes *b b*, and secured together at their lower ends, a single pin, D, adapted to be interchangeably inserted in either of the holes *b b*, and a series of wedges, *c c*, attached to a common carrier, all arranged and adapted to operate substantially as and for the purpose described.

In testimony whereof I have signed my name to this specification in the presence of two subscribing witnesses.

GALEN COFFIN.
